(57) **CLAIM**

The ornamental design for a lid of storage box, as shown and described.

DESCRIPTION

FIG. 1 is a top front perspective view of a lid of storage box showing my new design;

FIG. 2 is a front view thereof;

FIG. 3 is a rear view thereof;

FIG. 4 is a right side view thereof and the left side view being a mirror image;

FIG. 5 is a top view thereof;

FIG. 6 is a bottom view thereof; and,

FIG. 7 is a bottom rear perspective view thereof.

The dashed broken lines in the figures show portions of the lid of storage box that form no part of the claimed design. The shade lines in the figures are used to indicate the surface or shape of the lid of storage box and not surface ornamentation.
